UNITED STATES PATENT OFFICE.

HOWARD G. SHORTT, OF CARTHAGE, AND ALDERIC CORMIER, OF OGDENSBURG, NEW YORK, ASSIGNORS OF ONE-THIRD TO HIRAM SANDERS, OF CARTHAGE, NEW YORK.

FLUID-PRESSURE ALTERNATING MECHANISM FOR EQUILIBRIO ACTION.

Application filed January 24, 1924. Serial No. 688,239.

To all whom it may concern:

Be it known that we, HOWARD G. SHORTT and ALDERIC CORMIER, citizens, respectively, of the United States and of Canada, and 5 residents, respectively, of Carthage and Ogdensburg, in the counties of Jefferson and St. Lawrence and State of New York, have invented certain new and useful Improvements in Fluid-Pressure Alternating 10 Mechanism for Equilibrio Action, of which the following is a specification, reference being had therein to the accompanying drawing.

Our invention refers to a fluid pressure 15 alternating device or mechanism for synchronizing equilibrio action and is adapted for use with steam, water, all kinds of gases or fluids, and in fact is intended to be applied for handling any kind of liquid or 20 fluid or other similar substance or material, as, for example, the mechanism may serve in connection with a steam condensation plant, or a hot water heating system, or a water distribution apparatus, or any 25 other mechanism or device having like or similar objectives and purposes. One of the essential features is a duplicate or alternating system employing a plurality of two or more tanks, reservoirs or receivers which 30 receive the fluid or liquid in automatic alternation. The object of the invention is to provide a dual mechanism whose several members or units operate alternately or 35 separately in an automatic progression in accordance with the action of a fluid pressure, hydraulic or other regulating and governing valve, or an equivalent electrical substitute having the same function and purpose. And the invention may therefore be 40 said to consist essentially of a dual or multiple arrangement of tanks or receivers for water or other fluid, as, for example, the condensation water resulting from the condensation of steam, and means for introducing steam into the tanks separately for the 45 purpose of forcing out the contents of the tanks and carrying the same back to the feed-water holders, or to any other point for any other purpose; and the invention 50 may also be said to consist, moreover, in the numerous details and peculiarities in the construction, combination and arrangement of the various parts, substantially as will be

hereinafter described and then more fully pointed out in the claims. 55

In the accompanying drawing illustrating our invention:

Figure 1 is a front elevation of our improved fluid-pressure alternating mechanism. 60

Figure 2 is a vertical longitudinal section of the valve mechanism constituting the main portion of the invention, but omitting the tanks or receivers which are sufficiently delineated in Figure 1. 65

Figure 3 is an enlarged detail sectional view on the line 3, 3, of Figure 2 of one of the steam inlet valves for controlling the passage of high pressure steam into one of the tanks. 70

Figure 4 is a similar vertical section on an enlarged scale on the line 4, 4, of Figure 2, of one of the exhaust valves through which steam is vented from one of the tanks after having been used therein. 75

Figure 5 is an enlarged sectional view of a portion of one of the tanks and one of the operating valves associated therewith whereby fluid-pressure actuates the main piston belonging to the steam valve operating mechanism, and indicates the float or diaphragm located within the contents of the tank for the purpose of enabling the level of such contents to automatically actuate the aforesaid valve. 85

Figure 6 is a vertical longitudinal sectional view of the arrangement of valves for admitting and exhausting steam, similar to the arrangement shown in Figure 2 but having electrical devices actuated by float mechanisms in the tanks in lieu of the fluid-pressure piston shown in Figure 2. 90

Similar characters of reference designate corresponding parts throughout all the different figures of the drawing. 95

In the present example of our invention we have indicated two tanks, reservoirs or receivers A and B which may be taken as arranged in connection with a steam condensation plant. The condensation water flows into the tank A through pipe 14 and is ejected also from the tank through said pipe for the purpose of being distributed to a feed water heater or elsewhere, and the tank B is similarly equipped at the bottom 100 with the pipe 15 through which the con- 105

densation water flows into said tank and is ejected therefrom. Steam is allowed to enter the top of tank A at certain times through the steam inlet pipe *a* and the tank 5 B is similarly equipped with a steam inlet pipe *b* through which high pressure steam reaches the interior of said tank.

Arranged in connection with the steam pipe *a* is a valve casing C which is entered 10 by the pipe *c* which conveys high pressure steam and leads from the boiler or some point in the steam line. Said casing C also has a vent pipe *c*¹ through which the exhaust steam from the pipe *a* is delivered to 15 atmosphere. Similarly the pipe *b* is arranged in connection with valve casing D which is entered by a high pressure steam pipe *d* leading from the boiler or steam line, and casing D has a vent pipe *d*¹ through 20 which exhaust steam is vented at the proper time to the atmosphere from the pipe *b*. In the valve casing C (see Figure 2) there is a valve device for controlling the flow 25 of the live steam from the pipe *c* into the interior of the casing C so that it may have outlet from the pipe *a* into the tank A, and in casing C there is also another valve having the function of an outlet valve for allowing the waste steam which at times fills 30 the casing C from pipe *a* to pass out through said casing through the vent pipe *c*¹; and in like manner the casing D contains a valve for controlling the supply of live steam from 35 pipe *d* to pipe *b* and an exhaust or outlet valve for controlling the passage of the waste steam from the interior of the casing D to the vent pipe *d*¹.

Before explaining in greater detail the steam inlet and outlet valves just alluded 40 to, we will refer to the means for automatically operating the same in producing synchronous equilibrio action which consists, in one example of the invention, that shown in Figures 1 and 2, of a fluid-pressure piston and cylinder and suitable connecting pipes, and in another example of the invention, that shown in Figure 6, of electric circuits, electro-magnets and appurtenant devices, it being understood moreover that hydraulic devices may be substituted for the fluid-pressure mechanism and that in addition to these several specific kinds of mechanism, there may be quite a wide diversity of other substitute means employed for effectuating the same result in the automatic production of synchronous action.

In the fluid-pressure device delineated in Figures 1 and 2, 1 denotes a cylinder in which is a reciprocating piston 2 on one side of which is a chamber 3 and on the other side a chamber 3^a, said chambers being designed to receive fluid pressure, as air, which is delivered thereto respectively through the pipe 4 which enters the chamber 45 3 and the pipe 4^a which enters the chamber

3. These pipes 4 and 4^a run to points alongside of the tanks A and B, the pipe 4 entering the valve casing 11 which contains a valve device for controlling the passage of the air, said casing 11 being supported by bracket 27, or other means, on the side of the tank A, while the pipe 4^a leads to another casing 11 similarly supported on the tank B, said casing containing an air-controlling valve device. These air valves are 70 automatically actuated by means of a float, diaphragm or equivalent member 16, one of which is inside the tank A and the other inside the tank B, said floats 16 rising and falling with the level of the liquid contents 75 of the cylinders and opening and closing the aforesaid air valves in order that fluid pressure which is delivered to the valve casings 11 from pipes 13 running from some suitable air reservoir or supply may be delivered into said casings and thus, under 80 control of the valves, through the pipes 4 and 4^a, for the purpose of acting against the piston 2 and enabling it, through the medium of suitable leverage, to operate the 85 steam valves and permit high pressure steam to enter the tanks on top of the liquid contents thereof, in order to eject said contents through the outlet pipes 14 and 15, or other outlet means with which said tanks are provided, as we have already indicated. It will be understood, therefore, that the admission of steam to one tank or the other is 90 automatically effected by the action of the floats whenever the tanks have been filled 95 with condensation water to the point at which it becomes desirable to empty them, at which time the steam flows in quickly and with great force and causes the instantaneous discharge of the contents of the tank. 100

Proceeding to analyse the mechanical features whereof the alternating mechanism is composed in greater detail than we have done hereinabove, it will be noted by referring to Figure 5 that the side of the tank A is provided with a cover or plate 17 held 105 securely thereto by means of a series of bolts 18, but readily removable to allow access to the interior of the tank A when it is desired to insert or remove the float 16. This circular cover 17 has a protuberance 19 thereon in which is mounted a horizontal shaft 22, tightly packed in the bearing 23, said shaft 22 having a rocker arm 24 which is pivoted 110 to the cleft member 25 carried on the lower end of the valve stem 26, which belongs to the fluid-pressure valve mechanism. The horizontal shaft 22 is provided with a rod 21 which projects toward the interior of the tank and enters the tubular extension 115 20 on the float 16 so that an easy and effective connection, the parts of which are readily separable, may be made between the float 16 and the arm 21. It will be manifest that as the float rises and falls, due to the change 120

of the water level, the stem 26 of the fluid-pressure valve will rise and fall in sequence. Stem 26, as indicated in Figure 4 and in Figure 2, carries a valve 28 which functions in connection with a seat in the chamber 11^a of casing 11 and also another valve 29 which functions in connection with a seat in the chamber 11^c of casing 11, while the upper end 30 of stem 26 enters a guiding recess in the screw cap 31 which closes the top of the chamber 11^c. Said chamber 11^c is provided with an outlet pipe 12 through which the air can exhaust to the atmosphere when the valve 29 is open. Between the chambers 11^a and 11^c is an intermediate chamber 11^b in the casing 11 which is entered by the pipe 4 or the pipe 4^a accordingly as we may be describing the air valve belonging to the tank A or that belonging to the tank B. In each case the chamber 11^a which is the lowermost of the three chambers in the valve casing 11 is entered by the air-supply pipe 13. It is not necessary that the pressure in the reservoir from which the air is taken should be large, as a low pressure of from 20 to 30 pounds will usually be found sufficient for the purpose of supplying enough power to move the piston 2 and transmit motion therefrom to the steam valve devices. Thus it will be seen that the tanks A and B have each a fluid-pressure valve mechanism operated automatically by a float, diaphragm, or other device controlled by the water level, and that when the water level rises and the float rises with it, it will pull down the valve stem 26 and open the valve 28 so as to allow fluid pressure to pass from the chamber 11^a into the intermediate chamber 11^b and out through the pipe 4 or 4^a, as the case may be, and that when the float 16 again drops, due to the lowering of the water level, the valve 29 which has been previously closed so that the air could not escape to the atmosphere will now be lifted, as shown in Figure 5, where it is removed from its seat at the same time that the valve 28 is closed, and the pressure within the chamber 11^b will be allowed to exhaust into chamber 11^c and out to atmosphere through vent pipe 12. In this way the cylinder 1 is adequately vented.

Referring to the valve devices for introducing steam into the tanks A and B on top of the liquid contents therein, for the purpose of effectuating the discharge of such contents, we premise that each of the tanks has a steam admission and a steam vent valve, as already pointed out, one of the valve mechanisms being arranged in connection with the valve casing C and the other in connection with the valve casing D, the details thereof being fully delineated in Figures 2 and 6. The steam or pressure inlet valve 34 functions with relation to a seat 37 to permit steam to pass through pipe c into the chamber 38 whence it flows out

through pipe a. Valve 34 has a stem which is made in two parts placed end to end, one of these parts being designated 33 and the other 10, the latter being the lowermost part and passing out through the packing 32 in the lower end of the casing C, while directly above the stem section 10 is the stem section 33 which is secured to said valve 34, while directly above the valve 34 an integral member rises and terminates in the piston 35 which operates loosely within the upper portion of the valve casing and below the hollow cap 36 which is screwed into the top of the casing. The stem 33 is tubular, see Figure 3, and within the same is a three- or four-winged rod 40 having a round terminal at its lower end which closes the lower end of the tubular stem 33 when the rod 40 is lifted, and said rod 40 has also a terminal valve 41 at its upper end which plays back and forth with reference to a seat 42 in the center of the piston 35. At certain times, as we shall presently show, steam may circulate past the piston 35, for it is a loose fit, and flow under the hollow cap 36 and this steam can return when the valve 41 is opened by flowing past said valve and along the channels between the wings of the rod 40 through the tubular stem 33 and vent or exhaust through the lateral opening or openings 39 in said stem, all as clearly shown in Figure 3. When the stem section 10 reciprocates upwardly, therefore, it will lift the winged rod 40 and cause the lower end of the tubular stem 33 to be closed, thus opening the valve 41 at the same time that the valve 34 is lifted from its seat 37 by the action of the stem 10 on the lower end of stem 33, and conversely, when the stem 10 drops it is obvious that the winged rod 40 will drop until the valve 41 closes down on the seat 42 and the valve 34 closes down on the seat 37, these parts gravitating downwardly and being forced down by the exhaust pressure of the steam as soon as the stem section 10 drops.

It should be noted that a rocker arm 9 is pivoted near the bottom of the valve frame C and another one near the bottom of the valve frame D by means of a pivot pin 7 and that the middle portion 6 of rocker arm 9 has projecting therefrom an angular crank arm 8 which is pivoted to the piston rod 5 projecting to the left from the piston 2, in the one case, and in the other case, to the piston rod 5^a projecting to the right from the piston 2, so that the movement of the piston 2 towards the left will rock the left hand rocker arm 9 in one direction on its pivot and will similarly rock the right hand rocker arm 9 in the same direction on its pivot. Each valve stem 10 which we have been describing has at its lower end a slot 43 which engages a pin 44 projecting from the rocker arm 9 at one end thereof, while

at the other end of said rocker arm is another similar pin 44^a which engages a slot 43^a in the lower end of the companion valve stem section 10^a belonging to the steam exhaust valve, which is a counterpart in all respects of the steam inlet valve which we have just been describing.

In giving the details of the construction and arrangement of the steam outlet valve which enables the exhaust steam to pass to atmosphere, it will be seen, as we have said, that it is the same in all substantial respects as the steam inlet valve, having a valve member 34^a which functions in relation to a seat member 37^a through which the steam finds an outlet to the atmosphere from the chamber 38 through pipe c¹ when the companion steam inlet valve 34 has been closed. Valve 34^a has above the same a loose fitting piston section 35^a, which operates in the upper portion of the casing C immediately below the chambered cap 36^a, and the said valve 34^a has a tubular stem 33^a similar in all respects to the stem 33 and containing a winged rod 40^a similar to rod 40, which winged rod 40^a carries at its upper end a terminal valve 41^a which rises and falls with reference to its seat 42^a. Below the enlarged lower end of the winged rod 40^a the stem section 10^a plays up and down in the bearing 32 in the lower portion of casing C (or D, as the case may be). The upper end of the stem 10^a performs in relation to the stem 33^a and its inner winged rod 40^a the same functional activities that are performed by the stem 10 in relation to the stem 33 and other parts, and the lower end of the stem 10^a has a slot 43^a engaging a pin 44^a on the rocker arm 9. Obviously, therefore, in view of the relative arrangement of these parts, as we have just described them, the steam inlet valve 34 will be open at the time that the steam exhaust valve 34^a is closed and vice versa in consequence of the connection with the stem sections of the rocker arm 9. Furthermore, as will be clearly evident, the steam valve mechanism belonging to the tank A, while it is the same as the steam valve mechanism belonging to the tank B, each including a steam inlet valve and a steam exhaust valve which are similarly constructed, as shown, yet it should be evident by referring to Figures 2 and 6 and the details set forth on a larger scale in Figures 3 and 4 that by virtue of the fact that the actuating stems of one mechanism are operated similarly with the operating stems of the other mechanism, so long as a single piston with jointly movable rods is employed, which rods shift the rocker arms of both valve mechanisms in the same direction, when the steam inlet valve of one valve mechanism for one tank is open, the steam inlet valve of the valve mechanism for the other tank will be closed, and in order that this may be so the two steam inlet

valves have their valve rods attached to the outer ends of the rocker arms 9, while the two steam outlet valves have their valve stems attached to the inner ends of the said rocker arms 9, thus causing the steam outlet valves to be nearest each other when the parts of the invention are assembled and arranged as shown in Figures 2 and 6, and similarly the two steam inlet valves, being the outermost valves in the grouping of parts. Although this is the preferable arrangement, yet it is not essential that it should be carried out always in this way, though when a single fluid-pressure piston is employed for the purpose of actuating all these steam valves it would be necessary to arrange the parts so that the bell-crank devices or rocker arms may vibrate in the same way, because evidently when steam is being admitted to the full tank, it is desirable to simultaneously exhaust steam to the atmosphere from the empty tank and vice versa. It is unnecessary to go into a description of the details any further than we have already done in order to show clearly how these two valve mechanisms for the two tanks are twins in arrangement and function.

Referring again to Figures 3 and 4 and to the tubular construction of the valve stems 33 and 33^a belonging to the valves 34 and 34^a, the winged rods therein, etc., it will be noted that when the steam inlet valve 34 or the steam exhaust valve 34^a is closed tightly down upon its seat, the steam pressure will be on top of the same and will rise upwardly and flow past the loosely fitting pistons 35 or 35^a, as the case may be, into the chambers of the caps 36 or 36^a, the valve 41 or 41^a at this time being closed. When, however, the valve 34 or 34^a is lifted away from its seat, the valve 41 or 41^a will be opened and steam which is in the upper portion of these chambers and parts will pass down through the seat 42 or 42^a and out through the openings 39 or 39^a, as the case may be, so as to be disposed of in the natural way. For otherwise the steam would not have free employment through the channels and passages in the performance of its normal functions.

In Figure 6 I have shown electrical mechanism arranged as a substitute for the cylinder 1 and piston 2 which I have shown in Figures 1 and 2 as operated by air pressure. Of course it will be perceived that in lieu of air pressure, pressure may be exerted on the piston 2 by means of any other gas or the arrangement may be a hydraulic one, or any other liquid or fluid may be utilized for actuating the piston 2, but we find it extremely convenient to use at times the electrical mechanism shown in Figure 6 which is simple and efficient. In the tanks A and B are the floats 52 attached to the ends of stems or rods pivoted at 55, which stems or

rods carry at their ends insulated contact fingers 56 adapted to come into contact with the electrodes 57 which are shown as arranged in electric circuit having a suitable battery or other source of energy and suitable electro-magnets 48 and 49, which magnets when they are energized by the passing of the proper currents will attract the armature levers 53 or 54 on the opposite sides of 10 the opposite operating lever 47, which lever 47 stands in lieu of the piston 2 and has its upper end slotted at 51 to engage the pin 50 on a reciprocating member 46, the ends of which are pivotally connected with the bell 15 crank arms 8 of the rocker levers 9 for the purpose of imparting the proper joint action to the different valves of the duplicate valve mechanisms for the two tanks, all as shown in Figure 6, said valve mechanism being 20 the same in construction and arrangement as indicated in Figures 1 and 2.

The two tanks A and B being located in proper relation to the apparatus with which they are to perform their functions by way 25 of synchronizing equilibrio actions, will in the out-pumping of the condensed water gradually fill with said water and will obviously be alternative in their filling by reason of the flow of the water. When the tank 30 fills to the point of causing the float or diaphragm, or other automatic means therein to be lifted sufficiently high as to actuate the air valve mechanism, opening the same and letting air pressure pass through so as to 35 act upon the piston 2, or so as to cause one of the circuits in Figure 6 to be closed and the electro-magnet which is energized thereby caused to attract its armature and operate the leverage, the result will be that the 40 steam inlet valve for one tank will be opened while the steam exhaust valve for the same tank is closed, and the steam inlet valve for the other tank will be closed while the steam exhaust valve for that tank is open, whereby 45 any steam in the empty tank or the one that is partly empty will be vented while the full tank will receive steam pressure which will instantaneously act therein upon the liquid contents of the tank and discharge the same 50 through the piping arranged for the purpose, as we have explained, it being manifest that when a tank is emptied the falling of the float or equivalent device will cause the air valve to close its inlet member and 55 open its venting member and the supply of steam to the tank will be cut off because the valve mechanism will be reversed and the steam previously introduced will be vented to the atmosphere. Thus an orderly pro- 60 gression in the operation of the tanks will take place and the regular alternation in the filling and emptying of the same, for whenever a tank fills it will be quickly discharged by the fluid pressure introduced 65 thereinto on top of its contents and when so

discharged the actuating fluid pressure will afterwards be vented to the atmosphere.

Having thus described our invention, what we claim as new and desire to secure by Letters Patent, is:

1. In an alternating mechanism for equilibrio action of the kind described, the combination of a plurality of liquid-holding tanks, a buoyant member in each, an external air valve on each holder automatically controlled by the buoyant member, a cylinder and its piston, fluid pressure pipes running from the tanks to opposite ends of the cylinder to convey pressure to opposite sides of the piston, duplicate valve mechanisms 75 arranged in connection with each tank, and including a steam inlet valve for the tank and a steam outlet valve, and leverage connections between the aforesaid piston and the valve mechanisms, so that when the buoyant member actuates one of the fluid pressure valves the piston will be reciprocated to actuate one of the steam valve mechanisms.

2. In an alternating mechanism for equilibrio action of the kind described, the combination of a plurality of liquid-holding tanks, a cylinder and its piston, fluid pressure pipes leading from the source of supply to opposite sides of the piston, automatic valves operated from within the tanks by the changing of the liquid level for the purpose of controlling the passage of pressure through the aforesaid pipes to the different ends of the cylinder, a steam valve on each holder, and connections between said valve and the piston whereby the movement of the piston is enabled to introduce steam into one of the tanks.

3. In an alternating mechanism for equilibrio action of the kind described, the combination of a plurality of liquid-holding tanks, a cylinder and its piston reciprocable by fluid pressure, means for conveying fluid pressure from the source of supply to the opposite sides of the piston, float-operated valves for each tank arranged to control the fluid pressure in said means, said valves including a member admitting the passage of pressure to the cylinder and a member exhausting to atmosphere, and a steam valve for each tank together with suitable connections between said valve and the piston in order to enable the piston to open and close said valves.

4. In an alternating mechanism for equilibrio action of the kind described, the combination of a plurality of liquid-holding tanks, a cylinder and its piston reciprocable by fluid pressure, means for conveying fluid pressure from the source of supply to the opposite sides of the piston, float-operated valves for each tank arranged to control the fluid pressure in said means, said valves including a member admitting the passage of

pressure to the cylinder and a member exhausting to atmosphere, and a steam valve for each tank together with suitable connections between said valve and the piston in order to enable the piston to open and close said valves, each steam valve including a member for allowing the passage of steam into the tank and another member for allowing steam to exhaust to atmosphere.

5. In an alternating mechanism for equilibrio action of the kind described, the combination of a plurality of liquid tanks, a buoyant member in each, a cylinder and its piston reciprocable by fluid pressure, valve devices operated from within the tank by the buoyant member to control the flow of pressure to said cylinder, and steam valve mechanisms for each of the tanks, each valve mechanism comprising duplicate valves one of which allows the passage of steam to the tank and the other of which exhausts to the atmosphere, sectional valve stems for said valves, means for carrying the sections of each valve stem in rectilineal alignment with each other, and leverage mechanism between the ends of the valve stems and the piston, all arranged so that the steam valves may be actuated in correspondence with the changing level of the liquid within the tanks.

6. In an alternating mechanism for equilibrio action of the kind described, the combination of a plurality of tanks, a buoyant member in each, an external air valve on each tank automatically controlled by the buoyant member, a cylinder and its piston reciprocable by said fluid pressure accordingly as one or the other of the fluid pressure valves is actuated by one or the other of the buoyant members, steam valve devices arranged in connection with each of the tanks, those for each tank having duplicate valves, one controlling the admission of steam to the tank and the other venting it to the atmosphere, sectional valve stems for said valves, the sections belonging to each stem being in alignment with each other and suitably supported so that the stems may be parallel to each other, a piston rod projecting from each side of the piston, and crank levers pivoted to the ends of the piston rods and to the valve stems, whereby both valve mechanisms for both tanks may be jointly operated so that when steam is being admitted into one tank it will be exhausted from the other.

7. In an alternating mechanism for equilibrio action of the kind described, the combination of a plurality of liquid holders, a buoyant member in each, steam valve mechanisms arranged in connection with each of the holders and consisting of duplicate valves one of which admits live steam to the tank while the other exhausts it therefrom, mechanism operated by the buoyant mem-

bers and including a system of levers connecting with all of the different steam valves so that the changed level of the liquid in the tanks may operate the buoyant members and thereby actuate the steam valve mechanisms so that steam may be automatically introduced into the fullest tank and simultaneously exhausted from the empty tank, all substantially as described.

8. In an alternating mechanism of the kind described the combination of a number of tanks, a mechanism jointly operated from within each tank by the changing level of the liquid therein, means for introducing condensation or other water or liquid into the bottom of the tanks, a pipe system leading to the top of the tanks for conveying live steam thereto, a valve mechanism for controlling the passage of the live steam in connection with each tank, said valve mechanism being operated by the aforesaid automatic mechanism within the tanks, and comprising essentially a steam valve for admitting steam to the tank, and a similar valve for exhausting steam from the tank, said valves having sectional stems, together with bell crank levers pivoted to said stems and connected with the actuating mechanism so that when one member of each valve device is opened the other will be closed.

9. In an alternating mechanism of the kind described, the combination of a number of tanks, a mechanism jointly operated from within each tank by the changing level of the liquid therein, means for introducing condensation or other water or liquid into the bottom of the tanks, a pipe system leading to the top of the tanks for conveying live steam thereto, a valve mechanism for controlling the passage of the live steam in connection with each tank, said valve mechanism being operated by the aforesaid automatic mechanism within the tanks, and comprising essentially a steam valve for admitting steam to the tank, and a similar valve for exhausting steam from the tank, said valves having sectional stems, together with bell crank levers pivoted to said stems and connected with the actuating mechanism, so that when one member of each valve device is opened the other will be closed, and said valve devices having integral therewith loosely moving piston sections above the same, past which the steam is allowed to flow, valve casings for said valves having upper steam chambers together with seats for the valves, and underneath valves arranged in hollow portions of the stems and adapted to open to allow the release of the steam in the top chambers at certain times during the operation.

10. In an alternating mechanism of the kind described, the combination of a number of tanks, a mechanism jointly operated from within each tank by the changing level

of the liquid therein, means for introducing condensation or other water or liquid into the bottom of the tanks, a pipe system leading to the top of the tanks for conveying live steam thereto, a valve mechanism for controlling the passage of the live steam in connection with each tank, said valve mechanism being operated by the aforesaid automatic mechanism within the tanks, and comprising essentially a steam valve for admitting steam to the tank, and a similar valve for exhausting steam from the tank, valve stems formed in sections, the sections of each stem being in alignment with each other, and one of the sections of each stem being hollow, winged endwise-movable rods carrying valves and located within the hollow stem sections, loosely arranged pistons integral with the valve members above the latter and allowing the passage of steam by them, and valve casings providing seats for the valve members and cylindrical bearings within which the piston sections slide, all arranged so that the live steam may hold the valves closely to their seats as required and may flow past the piston sections, but will be released from the upper chambers through the valve within the stem whenever the valve member is open, all substantially as described.

In testimony whereof we hereunto affix our signatures.

HOWARD G. SHORTT.
ALDERIC CORMIER.
